OFFICE DICTATION MACHINE

Harper Landell, Philadelphia, Pa., assignor to The International Electronics Company, Philadelphia, Pa., a corporation of Pennsylvania

Application September 2, 1948, Serial No. 148,431

Term of patent 14 years

(Cl. D26—14)

To all whom it may concern:

Be it known, that I, Harper Landell, a citizen of the United States, residing at Philadelphia, in the county of Philadelphia and State of Pennsylvania, have invented a new, original, and ornamental Design for Office Dictation Machine, of which the following is a specification, reference being had to the accompanying drawings, forming a part thereof.

Figure 1 is a front perspective view of an office dictation machine showing my new design.

Figure 2 is an end elevational view of the machine shown in Figure 1, looking toward the end of the machine at the left of Figure 1.

I claim:

The ornamental design for an office dictation machine, as shown.

HARPER LANDELL.
